SWABBING METHOD FOR INITIATING GAS LIFT

Application filed July 18, 1927. Serial No. 206,676.

This invention relates to the so-called "gas lift" method of flowing deep wells, particularly oil wells, and has been designated to overcome the excess hydrostatic head of oil which ordinarily accumulates in such wells prior to starting gas lift and which ordinarily cannot be removed by direct application of a reasonable gas pressure in attempting to initiate gas lift.

10 Gas lift, as now commonly practiced, consists in passing gas under pressure into a well containing a flow tube, so that the gas passes around the lower end of the flow tube in a stream and in its passage atomizes the oil as fast as it is forced up to said tube end by the natural rock pressure in the well, the atomized oil being carried to the surface in the gas stream. The gas may be introduced either through the flow tube or through the 15 casing, the atomized oil being discharged from the other of the two; however, it is preferred usually to introduce the gas into the casing and discharge the oil from the flow tube.

20 But, as above indicated, the initiation of gas lift usually offers difficulties, due to the fact that during a preceding period of idleness a relatively great hydrostatic head of oil has accumulated in the well hole, which head 25 usually cannot be overcome by steady application of a moderate pressure to one side of the flow tube. This condition arises for the reason that, as pressure is applied to one side of the tube to depress the oil level therein, the 30 hydrostatic head increases in the other side, and, while some of the oil is forced back into the formation (depending upon the viscosity of the oil, the friction of the formation, and the like) the effective rock pressure in the 35 vicinity of the well increases until it is sufficient to balance the increased hydrostatic head. Thus, upon any attempt to start gas 40 lift by straight application of pressure to one side in order to force over the entire excess load of accumulated oil and uncover the lower end of the tube for passage of gas thereunder, the hydrostatic head will increase until it reaches the maximum, that is, until it is equal to the entire height of the 45 flow tube, which height may be as much as a

few thousand feet. This head may be greater than the available pressure. Moreover, the pressure which would be high enough to start gas lift by such steady application, that is, a "normal starting pressure," under these conditions, would be excessive for all other purposes, since when the oil level is lowered and gas lift started, normal continuation of gas lift may be and should be carried on with a much lower pressure, this being made possible by the much lower density of the gas-and-oil column in the flow tube during normal gas lift as compared with the oil before gas lift. Thus, it is clear that it is not convenient or desirable to maintain said excessive pressure merely for the purpose of overcoming said hydrostatic head.

55 The general object of the present invention, therefore, is to overcome the hydrostatic head and depress the oil level approximately to the lower end of the flow tube by the application of gas under a pressure less than that required to initiate gas lift by steady application to either the tube or the 60 casing in the usual manner, and less than merely for the purpose of overcoming said hydrostatic head.

70 The general object of the present invention, therefore, is to overcome the hydrostatic head and depress the oil level approximately to the lower end of the flow tube by the application of gas under a pressure less than that required to initiate gas lift by steady application to either the tube or the casing in the usual manner, and less than merely for the purpose of overcoming said hydrostatic head.

75 The present invention resides in initiating gas lift by introducing a swab into a flow tube to a point low enough to obtain a satisfactory load of oil and then withdrawing the swab from the tube while maintaining the maximum available pressure upon the casing. The withdrawal of the swab tends to reduce the pressure there beneath, whereby it is possible to cause the well to flow with the assistance of a gas pressure which is much less than sufficient to overcome the head of oil in the well when applied unassisted.

80 In the accompanying drawing wherein the steps in the operation of the method are diagrammatically illustrated;

85 Fig. 1 indicates the level to which the body of oil has risen in a well wherein the hydrostatic head is too great to be overcome by the available gas pressure;

90 Fig. 2 represents the introduction of a swab into the lower portion of the flow tube;

95 Fig. 3 shows the withdrawal of the swab from the flow tube simultaneously with the

100

application of pressure to the casing whereby the level of the oil body is lowered; and

Fig. 4 indicates the oil level when the excess has been entirely expelled and normal gas lift has been instituted.

An ordinary well casing 10 is shown as receiving flow tube 12 which depends into a body of oil which has risen in the casing to the level 14. Gas under pressure is adapted to be applied to the casing from a compressor 15 by way of an inlet 16. Since this pressure is insufficient to overcome the hydrostatic head, a swab 18 is lowered into the lower end of tube 12 by means of a line 20 until the desired load above the swab is obtained. The gas under pressure from the compressor 15 is supplied to build up in the casing as high a pressure as possible and the swab 18 is then withdrawn rapidly from the flow tube. The tendency of the withdrawal is to create a lower pressure beneath the swab and to draw a column of oil up through the lower portion of the tube. This effect is assisted by the gas pressure being applied upon the surface of the oil in the casing, with the result that in most instances the combined effect is sufficient to force over the oil column and flow out the accumulated oil body. If flow cannot be established in one operation, the swabbing may be repeated until the head of oil is sufficiently lowered. When the combined effect of the swabbing and gas pressure becomes sufficient to overcome the head, the flow ordinarily starts with a rush and often forcibly expels the swabs from the flow tube, the accumulated oil body being rapidly discharged whereby the oil level is brought down to the lower end of the tube as indicated in Fig. 4. The gas being introduced into the casing then passes beneath the end of said flow tube and in its passage aerates or atomizes the oil as it flows into the well thereby initiating normal gas lift and maintaining the oil level at approximately the lower end of the tube. To continue gas lift a pressure lower than the starting pressure ordinarily will be employed.

Since a swab is a long stroke pump, the invention in its broadest aspect extends to the use of pumping in connection with applied gas pressure for the purpose of starting a well. Moreover the employment of a true pump during application of pressure will often cause a well to flow, in which case the pump rod, valves and associated mechanism are withdrawn from the pump barrel when flow becomes established.

This method very frequently may be conveniently used for reducing static head preparatory to gas lift initiation and is relatively easy and simple to perform. It may be employed where effective pressure, when steadily applied, is not sufficient to start gas lift by reason of any one of the following causes:

Loss of pressure due to the escape of gas into open sands;

Loss of pressure due to leakage of gas from the casing;

Insufficient gas volume;

Pressure inadequate to overcome the static head of the accumulated oil.

Usually swabbing will relieve the static head sufficiently to enable the effective pressure in conjunction with the swabbing effects to kick over the oil column and clear the well as above described.

Preferably, natural gas is employed, but air or other gas may be used. Also gas may be introduced from an adjacent well if the pressure is sufficiently high, thereby eliminating the compressor.

As specific examples, a well which would not start on straight application of 820 pounds on the casing, was swabbed with 725 pounds on the casing, and the well immediately began to flow, gas lift being then continued with 200 pounds. Again where 800 pounds was insufficient on straight application, the well began to flow with 300 pounds on the casing, and gas lift was continued thereafter with 150 pounds.

It is to be understood that the above disclosures are considered merely as illustrative and not as limiting, since many variations of the invention may be made within the scope of the following claims.

I claim:

1. A method for initiating gas lift in wells containing a liquid head comprising simultaneously swabbing and applying to the liquid surface gas under pressure from an outside source.

2. A method for initiating gas lift in oil wells containing a liquid head comprising reducing the effective static head by swabbing and simultaneously applying to the liquid surface gas under pressure from an outside source until flow is established.

3. A method for initiating gas lift in oil wells containing a liquid head which comprises reducing the static head of oil in a well by swabbing to a point sufficient for the initiation of gas lift when gas at a predetermined pressure is applied to the oil surface from an outside source, and so applying gas at the predetermined pressure to the oil surface from the outside source.

4. A method for initiating gas lift in an oil well having a casing through which a flow tube depends into a body of oil in the casing, comprising introducing a swab into the tube, withdrawing the swab to remove a quantity of oil and reduce the static head in the tube, and simultaneously applying gas from an outside source under pressure to the surface of the oil in the casing to assist the swabbing action and to start gas lift.

5. A method for initiating gas lift in an oil well having a casing in which a tube depends into a body of oil, comprising applying gas from an outside source under pres-

sure to the oil surface on the outside of the tube and simultaneously mechanically pumping oil out through the tube with a reciprocating piston pump working upon the oil until gas lift is established.

- 5 6. A method for effecting gas lift in an oil well having a casing in which a tube depends into a body of oil, comprising applying gas from an outside source under pressure to the oil surface on the outside of the tube and simultaneously pumping oil out through the tube until gas lift is established and then discontinuing the pumping while maintaining the gas pressure to continue gas lift.
- 10 7. A method for effecting gas lift in an oil well having a casing in which a tube depends into an oil body, comprising applying gas from an outside source under pressure to the oil on the outside of the tube and simultaneously withdrawing quantities of oil from the tube to reduce the hydrostatic head in the tube without admitting gas to the tube, discontinuing the withdrawal of said quantities of oil when said gas enters the tube, and
- 20 25 maintaining the gas pressure to initiate and continue the flowing of the well by gas lift at said reduced head.

Signed at Los Angeles, in the county of Los Angeles and State of California, this 12th day of July, A. D. 1927.
